UNITED STATES PATENT OFFICE

135,247

DESIGN FOR A CRUCIFIX

James P. Calnan, Belmont, Mass.

Application August 21, 1942, Serial No. 107,990

Term of patent 14 years

To all whom it may concern:

Be it known that I, James P. Calnan, a citizen of the United States, residing at Belmont, in the county of Middlesex and State of Massachusetts, have invented a new, original, and ornamental Design for a Crucifix, of which the following is a specification, reference being had to the accompanying drawing, forming part thereof.

In the drawing.

Fig. 1 is a plan view of a crucifix showing my new design; and

Fig. 2 is a sectional view on line 2—2 of Fig. 1.

I claim:

The ornamental design for a crucifix or similar article, substantially as shown.

JAMES P. CALNAN.
